FOLDING BED

Martin D. Miesner, Berkeley, Calif.

Application November 1, 1946, Serial No. 707,080

6 Claims. (Cl. 5—6)

1

The invention relates to the frame structure of a folding bed.

An object of the invention is to provide a folding bed structure which is concealedly foldable into a cabinet having the appearance of a stand or the like.

Another object is to provide for a folding of the bed into a particularly small space.

A further object is to provide a folding bed of the character described which is particularly strong and rigid when unfolded for its use.

Another object is to provide a folding bed structure in which the unfolding and folding of the bed and the opening and closing of the cabinet are mutually coordinated in a particularly effective manner.

The invention possesses other objects and features of advantage, some of which, with the foregoing, will be set forth or be apparent in the following description thereof, and in the accompanying drawings, in which

Figure 1 is a plan view of the unfolded bed frame and a plan section of the cabinet taken generally at the line 1—1 in Figure 2.

Figure 2 is a side view showing the unfolded bed frame and a sectional elevation of the cabinet from which the frame is extended.

Figure 3 is an enlarged fragmentary sectional view at the line 3—3 in Figure 1.

Figure 4 is a view of the structure of Figure 3, a footboard member being shown as folded upon the bedding.

Figure 5 is a side view of the bed frame in fully folded condition, and as fully enclosed within the cabinet.

Figure 6 is a side elevation of the folded frame following an opening of the cabinet or preceding a closing of the cabinet.

Figure 7 is a fragmentary elevation taken at the line 7—7 in Figure 6.

Figure 8 is a fragmentary elevation taken at the broken line 8—8 in Figure 6.

Figure 9 is an enlarged fragmentary section at the line 9—9 in Figure 6.

By reference to the drawings it will be seen that the present bed frame generally comprises a plurality of sections which are hingedly related for coplanar extension to support bedding as a made-up bed for use, or be rolled up with the bedding for concealment within a cabinet. The bed frame comprises a foot section 11, intermediate sections 12 and 13 and a head section 14, and the four sections are hingedly attached in order for their relative swinging about mu-

2

tually parallel axes between folded and unfolded relations thereof.

The present foot section 11 comprises side members 15 and a connecting cross member 16 defining the foot end of the frame. Preferably, and as shown, the side members 15 are of angle section having corresponding flanges 15' thereof define the section side boundaries while their other flanges 15'' are mutually coplanar at the bottom of the section when the frame is extended. The present cross member 16 is also of angle section and has the extremities of the bottom flanges 15'' fixed to and upon its bottom flange 16'', while the ends of its other flange 16' are cut away to permit the mounting of a footboard assembly 17 on and between the flanges 15' for swinging between operative and inoperative positions thereof.

The footboard assembly 17 comprises L-shaped side arms 18 extending from a hinged connection of the extremities of portions 18' with the frame sides 15 adjacent the member 16, and carry a connecting footboard 19 between their other portions 18''. Pivot pins 20 connect the arm portions 18' to the flanges 15' at the inner faces of said flanges, and tension springs 21 connect the arm portions 18' with anchorages in the flanges 15'' in such a manner that the lines of the springs 21 lie at opposite sides of the common axial line of the pins 20 when the footboard is erected for use or disposed opposite the frame section 11; see Figures 3 and 4. The flanges 15'' are cooperative with the arm portions 18' as stops to limit the extended disposal of the footboard to a desired operative position, and the footboard 19 is arranged to operate as a spring-pressed clamp jaw upon bedding mounted on the frame when it is folded down upon the bedding; it will be understood that the action of the spring 21 is operative to yieldingly urge the disposal of the footboard in either of its limiting positions.

The frame section 12 comprises side members 23 of angle section hingedly connected to and between the sections 11 and 13, while the section 13 comprises side members 24 connected by a spreader bar 25 at connections 25' therefor, the members 24 being of angle section and being mutually positioned and spaced as the side members 15 of the foot section 11 for a mutual alignment of corresponding said side members when the frame is fully extended. The side members 23 of the section 12 have their coplanar flanges 23'' arranged for abutting engagement 55 with the opposed ends of the flanges 15'' and

flanges 23" of the side members 15 and 23 respectively when their frame is extended, and have the flanges 23' thereof connected to the flanges 15' and 24' of the frame members 15 and 24 in lapped relation thereto by means of pivot pins 26 and 27 respectively. The hinged connections at the pivot pins 26 and 27 are such as to limit a relative swinging of the connected sections into coplanar relation in an unfolding direction while permitting their swinging into angular relation for a folding of the frame.

The head-end section 14 comprises mutually opposed side members 28 of angle section fixedly connected by a head cross-member 29 of the frame, said side members being spaced as are the members 23 of the frame section 12 and having the foot ends of their mutually parallel flanges 28' extending inwardly of and pivotally connected with the head ends of the flanges 24' of the members 24 of the section 13 by means of pivot pins 31 engaged between their upright flanges 28' and the opposed flanges 24' of the members 24. When the section 14 is coplanar with the section 13, the bottom flanges 28" of the members 28 are arranged to abut the ends of the corresponding flanges 24" of the members 24 as a means to limit the relative swinging of the members in an unfolding direction while permitting a hinging action in the folding direction.

It will now be noted that the folded bed frame structure is arranged to be supported in a cabinet which is closable to conceal the bed and present the appearance of a stand or dresser or other usual piece of household furniture. In the present structure, members 32 extend transversely from and along the outer faces of the flanges 28' for guided and sliding engagement with horizontal channel tracks 33 carried by the sides of a cabinet 34 of the bed assembly. As particularly shown, the members 32 extend laterally from the tops of the flanges 28' whereby the members 28 are of Z-bar section thereat, and the tracks 33 are mounted on pairs of mutually spaced offset brackets 33'.

When the present bed is fully extended, as is shown in Figures 1 and 2, the sections 11 and 12 and 13 and 14 are coplanar in a plane including or parallel to the plane of support provided by the tracks 32, and means are provided for supporting the sections 11 and 12 and 13 directly from the same floor surface which supports the cabinet 34. As particularly shown, the frame sections 11 and 13 are provided with legs 35 and 36 hingedly pivoted to their side members 15 and 24 respectively and disposable transversely of the extended frame for the support of the latter or foldable opposite the members 15 and 24 when the bed is folded, the positions of the legs 35 and 36 with respect to the sections 12 and 14 being automatically determined by the angular relation of the sections 11 and 13 with reference to the sections 12 and 14 respectively.

In the present structure, the pivot pins 20 are utilized as hinge pins for the legs 35, and said legs are extended beyond their pivot points to provide lateral extensions 37 which are arranged to be disposed above the level of the members 15 and are directed toward the head end of the bed when the legs are extended from the frame sections to which they are attached. Links 38 extend from pivot pins 39 at the free ends of the

extensions 37 to connections with pivot pins 40 mounted in the flanges 23' of the section 12. The arrangement is such that when sections 11 and 12 are coplanar, the legs 35 extend transversely from the section 11 as a support means, and are automatically folded into positions generally opposite the adjacent members 15 when the sections are mutually perpendicular. The legs 36 are generally similar to the legs 35 and are connected to the members 24 of the section 13 at pivot pins 42. Lateral extensions 43 of the legs 36 are connected with the members 28 of the section 14 by means of links 44 connected to the extensions and members at pivot pins 45 and 46 respectively, the control for the legs 36 corresponding to that for the legs 35.

Aside from their leg-positioning functions, the links 38 and 44 are operative to stiffen the extended frame against buckling at the pivot pins 26 and 31, and to that end are somewhat L-shaped, having lateral extensions 38' and 44' connected with the pins 26 and 31 at their free ends. In the present structure the link portions 38' and 44' are disposed opposite the inner faces of the flanges 23' and 28' to which they are respectively attached, and their links accordingly cross over the different section flanges which they respectively connect. By reason of the particular and similar leg-control connections provided by the pairs of links 38 and 44, it will be understood that localized pressure on the frame sections between the legs 35 and 36, or between the legs 36 and the support track 33 may not bend or buckle the frame at a pivot pin 26 or 31 respectively.

The present frame, comprising the succession of connected sections 11 and 12 and 13 and 14, serves directly as the frame of a spring mattress 47 which is foldable with the frame and is of the link type having intersecting lines of interconnected links 48 attached at their ends to the bounding elements of the frame through tension springs 49 to provide a yielding support for bedding including a usual soft mattress. The spreader bar 25 of the section 13, and any other intermediate spreader bars which may be provided in the frame structure, are offset downwardly between their ends to permit depressions of the bedding and spring mattress under the body of a person reposing thereon. Since, however, the section 13 is to provide one side of the folded frame structure, the bar connections 25' preferably comprise free swivel connections with the flanges 24" such that the plane of the bar may remain upright under the influence of gravity when the section is in either its extended or folded position; in this manner, the spreader is operatively disposed when the frame is extended, yet does not protrude from the section 13 when the frame is folded up.

Having the bedding disposed on the extended frame, the footboard 19 may be clampingly disposed against the bedding at the foot of the bed, and the frame may then be progressively folded up from the foot and into a compact roll of substantially rectangular prism outline as is illustrated in Figures 3 and 5. In folding the frame, it is desirable that the section 11 be moved into its final folded relation of perpendicularity to the section 12 before the latter section is raised with respect to the section 13, and to this end the pivot pins 26 preferably connect the side members of the sections 11 and 12 at points thereof which are appreciably closer to the flanges 15" than are

the pivot pins 40 for the leg-positioning links 38 to the flanges 23".

In the present structure, the foot section 11 is somewhat shorter than the section 13, and a rest is provided on the head section 14 for engaging the end member 16 of the section 11 to support the latter in upright position when the bed is folded. As particularly shown, post members 51 extend upwardly from the free corners of the head section 14 and mount support shelves or brackets 52 extending therefrom toward the foot end of the section for functioning as a seat to receive the free corners of the section 11; in the present structure the shelves 52 comprise intermediate portions of Z-shaped members 53 which extend between points of attachment to the post 51 and the section side members 28 and brace the posts as well as provide the seat. The lengths of the four frame sections are such that successive sections are substantially perpendicular when the frame is folded.

It will now be noted that the cabinet 34 comprises side panels 54 which mount the track-supporting brackets 33', a back panel 55 fixedly connecting the side panels 54, a top member 56 connecting the panels 54 and extending forwardly from the top of the back panel 55, a tie member 57 connecting the side panels 54 near their bottoms, a front panel 58 extending between the side panels 54 and hinged to the latter panels at its bottom as a drop front for its swinging to and from an upright position in which it comprises the front of the closed cabinet, and a forward top section 59 hingedly attached to the side panels 54 and arranged for swinging upwardly from a position in which it rests upon the top of the operative front panel 58. As is particularly brought out in Figure 3, the space of the cabinet 34 is arranged to completely receive and conceal the folded-up bed assembly when the front panel 58 and the top section 59 are cooperative as closure members for said space. The exterior surfaces of the cabinet may be finished in any desired manner, and the closed cabinet may appear as an article of furniture; in the present structure, the outer face of the front panel 58 presents the appearance of a drawer front whereby the closed cabinet resembles a dresser in appearance while its top may be used as the top of a stand.

The hinged mounting of the front panel 58 is provided by means of mutually coaxial pivot pins 61 connecting brackets 62 and 63 fixed respectively to the inner face of the panel 58 and the inner faces of the cabinet sides 54. Each pivot pin 61 is disposed inwardly of and adjacent a forward track-supporting bracket 33' whereby an element 64 of the bracket 62 which receives the pin 61 as a hinge support for the cabinet front 58 may engage the adjacent track-supporting bracket 33' as a stop to limit the lowering of the cabinet front to a horizontal position, as in Figure 5. It will be understood that the bracket members 62 and 63 comprise hinge leaves with respect to the hinged mounting of the front panel 58 on the cabinet.

It will now be noted that the pin-carrying element 64 of each member 62 extends transversely from a base element 66 suitably fixed to the back of the front panel 58, the plane of the elements 64 and 66 being parallel to the side edges of the panel. The outer portion 64' of each element 64 is curved toward the top edge of the panel 58, while the remaining portion 64'' is straight and provides the bearing opening for the hinge pin

61. The upper end of the base element 66 is connected with an intermediate point of the curved portion 64' of the element 64 by a strut member 67 riveted to the elements, the member 62 thus comprising a bracket which is rigid in its plane. Links 68 connect the outer ends of the elements 64 to the head posts 51 of the bed frame, pivot pins 68' and 68'' being provided at the respective connections. The arrangement is such that the head section 14 of the bed frame is pulled about half-way out on the support tracks 33 when the front panel 58 is swung out from the cabinet to the limiting horizontal position shown for it in Figures 2 and 5, and is disposed entirely within the cabinet space when the front panel 58 is erect in its cabinet-closing position; the lowered panel is preferably spaced from the floor while far enough below the frame assembly to permit in use depression of the spring portion above it. A link 69 connects a point of each element 64 between its terminal pivot 68' and its connection with the strut 67 with the top section 59 near its free edge, whereby a swinging of the front panel 58 between open and closed positions will correspondingly swing the top section 59 between open and closed positions. As shown, a pivot pin 69' connects the link 69 to the element 64 while a pivot pin 69'' connects the link 69 to a member 70 fixed to the under side of the cover section 59. The present linkage of the drop front 58 with the bed frame is such that a folding or unfolding of the bed assembly may be accomplished with a minimum of effort despite the lack of any counterbalancing springs.

Having the cabinet closed about the folded up bed assembly, as in Figures 3 and 4, a swinging down of the drop front 58 is arranged to extend the folded bed assembly forwardly from the cabinet while raising the front top section 59 to the illustrated position. This automatically accomplished forward positioning of the folded bed and lifting of the top section 59 when the front 58 is lowered serves to provide clearance for the required unrolling extension of the bed for its use, or the rolling up of the bed for its concealment within the closed cabinet, while providing clearance at the head of the extended bed. It will be understood, however, that the head frame section 14 might be fixed in the cabinet; in the latter event, the top section 59, while under the control of links operating as the links 69, must be higher and/or wider to provide the necessary clearance for an unfolding or folding of the bed while the cabinet front 58 is lowered.

From the foregoing description taken in connection with the accompanying drawings, the advantages of the construction and use of the present folding bed will be readily understood by those skilled in the art to which the invention appertains. While I have described the principle of operation, together with an arrangement which I now consider to be a preferred embodiment thereof, I desire to have it understood that the showings are primarily illustrative, and that such changes and developments may be made, when desired, as fall within the scope of the following claims.

I claim:

1. In a folding-bed frame, head and foot sections, a pair of hingedly connected intermediate sections, means hinging the different intermediate sections to the head and foot sections to provide for an extension of the frame with the sections in mutually coplanar relation or a folding of the frame with successive sections in mutual-

ly perpendicular relation, a cabinet having a drop front, support means on the cabinet, said support means slidably carrying the head section of the frame in horizontal position for its partial extension from the cabinet cavity, and link connections operative between the head frame section and the cabinet front whereby a lowering movement of the cabinet front is arranged to project the folded bed frame from the cabinet and a closing movement of the cabinet front is arranged to withdraw the folded frame within the cabinet space.

2. The structure of claim 1 having the link connections comprising an arm extending transversely of and rigidly from the head frame member and a link connecting the arm with the cabinet front.

3. In a folding-bed frame, head and foot sections, a pair of hingedly connected intermediate sections, means hinging the different intermediate sections to the head and foot sections to provide for an extension of the frame with the sections in mutually coplanar relation or a folding of the frame with successive sections in mutually prependicular relation, a cabinet having a drop front member and an upwardly swingable top member, a support means of the cabinet slidably carrying the head section of the frame in horizontal position for its partial extension from the cabinet cavity, and link connections operative between the head frame section and said cabinet front and top members whereby a lowering movement of the cabinet front is arranged to project the folding-bed frame from the cabinet and raise the top member and a closing movement of the cabinet front is arranged to withdraw the folded frame within the cabinet space and lower the top member.

4. In a folding-bed frame, a head section providing a support bracket in fixed transversely offset relation to it, means constantly supporting the head section in horizontal position with said bracket above it, a foot section, a pair of mutually hinged intermediate sections hinged to the head and foot sections for an extension of the frame with the foot and intermediate sections in coplanar relation with the head section or for a folding of the frame to dispose successive sections in mutually perpendicular relation with the foot section directly supported in upright position upon said bracket.

5. A folding-bed frame solely comprising a head section and two intermediate sections and a foot section directly hinged together in their order for an extension of the frame with the sections in mutually coplanar relation or for a folding of the frame to dispose successive sections to have the longitudinal lines thereof defining the sides of a quadrangle, means mounting the head section in constantly horizontal position, and means whereby the intermediate and foot sections are supported solely from the head section when the frame is folded.

6. A folding-bed frame solely comprising a head section and two intermediate sections and a foot section directly hinged together in their order for an extension of the frame with the sections in mutually coplanar relation or for a folding of the frame to dispose successive sections to have the longitudinal lines thereof defining the sides of a quadrangle with the intermediate and foot sections supported entirely from the head section, a cabinet having a drop front, a support means on the cabinet, said support means slidably mounting the head section in constantly horizontal position for its longitudinal adjustment between fully retracted and forwardly extended positions with respect to the cabinet space, and a link means cooperative between the head section and cabinet front whereby a lowering movement of the cabinet front is arranged to project the folded bed frame from the cabinet and a closing movement of the cabinet front is arranged to withdraw the folded frame within the cabinet space.

35 MARTIN D. MIESNER.
